UNITED STATES PATENT OFFICE.

BENJAMIN F. HAMILTON, OF LAWRENCE, MASSACHUSETTS.

ELEVATED RAILWAY STRUCTURE.

SPECIFICATION forming part of Letters Patent No. 376,986, dated January 24, 1888.

Application filed July 8, 1887. Serial No. 243,712. (No model.)

To all whom it may concern:

Be it known that I, BENJAMIN F. HAMILTON, of Lawrence, county of Essex, and State of Massachusetts, have invented an Improvement in Elevated Railway Structures, of which the following description, in connection with the accompanying drawings, is a specification, like letters on the drawings representing like parts.

10 This invention has for its object to improve the construction of elevated railways adapted for suspended cars; and it consists in the combination, with the main vertical uprights, the foundation-beams, and foundation brace-rods for the vertical uprights, of two truss-frames supported by the vertical uprights upon supporting-beams, brace-rods for said supporting-beams, and stay-bars and binding-rods connecting the two truss-frames, all as will be herein-
15 after more fully described, and pointed out in the claims at the end of this specification.

Figure 1 shows in side elevation a section of an elevated railway structure embodying this invention, it showing two vertical uprights 25 and the connected truss-frames; Fig. 2, an end view of the section of elevated railway structure shown in Fig. 1; Fig. 3, a top view of the truss-frame removed, showing the intermediate connecting-rods and braces; and Fig. 4, a cross-section of the truss-frames, taken on the dotted line $x-x$, Fig. 3.

The vertical supports each consist of two upright beams, A A', placed side by side, but separated a short distance at their lower ends, 35 as shown in Fig. 2.

The adjacent faces of the uprights A A' are cut away to receive between them key-blocks A², two of said key-blocks being herein shown.

The lower ends of the uprights A A' enter 40 mortises cut in a foundation-beam, A³, which beam is secured to a suitable base of masonry or equivalent in any suitable manner, as by bolts 2.

Brace-rods A⁴ are placed in position bearing 45 against the uprights A A' and the foundation-beam A³. Metallic strips 3 partially surround the uprights A A' and the foundation-beam A³, which strips are joined by stay-rods 4, having suitable turn-buckles, 5, for tightening 50 ing the said rods.

A collar, A⁵, surrounds the uprights A A' just at or above the points where the strips 3

and the brace-bars A⁴ are connected with said uprights, which, it will be understood, is substantially at the surface of the ground, as it is 55 desired that the entire foundation for the uprights should be beneath the surface of the ground.

A supporting-beam, B, is mortised at its center to receive the upper end of the uprights A A', said supporting-beam being braced by two brace-bars, B', bearing against the under side of the supporting beam and against the uprights A A', said brace-bars being held in fixed position by suitable bolts. Two supporting-beams, B², are placed beneath and parallel with the supporting-beam B, it being secured to the brace-bars B' by suitable bolts.

Two truss-frames rest one upon each end of the supporting-beams B B², each of said truss-frames consisting of two horizontal parallel beams, C C', connected by cross-bars c c, which bear against the blocks c', secured to said horizontal beam C; also by the binding-rods c², which are tightened by turn-buckles c³, the said binding-rods entering the blocks c', or passing through said blocks into the beams C C'. The beam C of each truss-frame rests upon the top of the supporting-beam B, and the beam C' is held up against the under side of the supporting-beams B². The two beams C C' are also joined by binding-rods d, which are tightened by turn-buckles d', a vertical supporting-rod, d², being placed between the two beams adjacent to the binding-rods d to limit the movement of the said beams toward each other.

The two truss-frames thus described being placed in position upon the supporting-beams of the vertical uprights, they are joined by the stay or cross bars f f', placed at short intervals apart, and also each corresponding pair of beams C C' of the truss-frames are joined by the binding-rods i, there preferably being four such binding-rods between each pair of cross-bars f f', said binding-rods being loosely 95 connected with the corresponding beams of each truss at a point near the junction of the cross-bars f f' and the beams, the opposite ends of the binding-rods i passing inward toward a central point between each pair of cross-bars and beams and fastened to a ring, i', by suitable nuts, so that by turning the said nuts within the ring the binding-rods may be tightened. The railway structure may be thus

made of any suitable length, the vertical uprights or supports being placed at short distances apart and the brace-frames, constructed as described and united to each other, being 5 supported by said uprights.

It will be seen that by the construction of the uprights and their foundation beams and braces, and also by the construction of the truss-frames and their supporting-beams and 10 braces mounted upon the supports, they are all made with a view to obtain the greatest amount of strength and durability in as simple a manner as possible.

The rails for the suspended cars are fixed to 15 the beams $c\ c'$ one above the other, to thereby form two tracks, one at each side of the vertical supporting-beams.

I claim—

1. In an elevated railway structure, the main 20 vertical supports and truss-frames supported by them, said main vertical supports consisting of two uprights, $A\ A'$, having a narrow space between them gradually increasing in width toward the lower ends, and key-blocks 25 fitted into and between the uprights, combined with the foundation-beam and brace-rods, substantially as and for the purpose specified.

2. In an elevated railway structure, the main vertical supports, each consisting of two uprights placed side by side, but separated somewhat at their lower ends, combined with the foundation-beam A^3 , brace-bars A^4 and binding-rods, and means for securing the foundation-beam rigidly in position, substantially as 30 described.

3. In an elevated railway structure, the main vertical supports, each consisting of two uprights placed side by side, but separated somewhat at their lower ends, and key-blocks A^2 , and bolts passing through the uprights, combined with the foundation-beam A^3 , brace-bars A^4 and binding-rods, and means for securing the foundation-beam rigidly in position, substantially as described. 4C

4. In an elevated railway structure, the main 45 vertical supports and their foundation beams and braces, combined with the supporting-beams $B\ B^2$ and braces therefor, and the truss-frames supported upon the beams $B\ B^2$, the cross-bar and binding-rods forming component 50 parts of the truss-frames, and the cross-bars and binding-rods for joining the said truss-frames, substantially as described.

5. In an elevated railway structure, the main vertical supports and their foundation beams 55 and braces, combined with the supporting-beams $B\ B^2$ and braces therefor, and the truss-frames supported upon the beams $B\ B^2$, the cross-bars and binding-rods forming component 60 parts of the truss-frames, cross-bar ff' , the binding-rods i , and the ring i' , for joining the two truss-frames, substantially as described.

In testimony whereof I have signed my name to this specification in the presence of two subscribing witnesses.

BENJAMIN F. HAMILTON.
